UNITED STATES PATENT OFFICE.

LOUIS A. DALL, OF OLMSTEAD FALLS, OHIO.

LATHE OR GRINDER ATTACHMENT.

Application filed July 2, 1927. Serial No. 203,121.

This invention relates to an improved and novel attachment for metal working machines and particularly to a device for use in connection with a lathe or grinder for finishing or 5 grinding pistons, having in view primarily a simple inexpensive and efficient appliance capable of use with standard machine shop equipment.

Another important object accomplished by 10 the use of the present invention, by reason of the novel construction and arrangement of parts, is that the pistons are accurately centered and rotated for grinding without distortion, which is absolutely necessary to the 15 production of a true and accurately balanced piston.

Another object is to provide such a device, whereby upon the interchanging of certain parts in an expeditious and simple manner, 20 the same can be adapted for use in connection with pistons of various sizes and the time usually required for changing the set up to suit different sized pistons is reduced to a minimum.

25 Another object is the production of a device of this character formed of very few simple but well designed parts capable of being quickly assembled into a strong compact balanced unit whereby the breaking factor will 30 be substantially nil.

The preferred embodiment of the invention is illustrated in the accompanying drawings, in which—

Fig. 1 is a view partly in section and partly 35 in elevation, clearly showing the assembled relation of the various parts in operative position with respect to the associated work piece or piston;

Fig. 2 is a top plan view;

40 Fig. 3 is a sectional view on line 3—3 of Fig. 1;

Fig. 4 is a side elevation of the main part of the device or spindle; and

45 Fig. 5 is an end view of the enlarged portion of said spindle;

Fig. 6 is an enlarged end view of the annular centering member or adapter removably carried by the spindle;

50 Fig. 7 is a side elevation of the fork shaped member or driver, adapted to be inserted in the enlarged end of the spindle as shown in Fig. 1; and

Fig. 8 is an end view thereof.

55 Referring to the drawings in detail the novel device, comprises a main portion or spindle 1 provided with a tapered shank 2

and an enlarged tapered head 4, said enlarged head portion being provided with a concentrically arranged noncircular chamber or recess 5. The tapered end of this spindle is standard 60 for insertion in a head stock of a lathe or grinder to be rotatably driven thereby in the usual manner.

Supported upon the enlarged tapered head 4 of the spindle is an annular member 6 said member being constructed with a tapered bore corresponding to the taper formed on the enlarged end 4 of said spindle. This annular member 6 is removably secured in position, preferably by a pin and cam-slot arrangement, the spindle 1 being provided with a curved slot 7 and the annular member 6 with a cooperating inwardly projecting pin 8, whereby a partial rotation of the member 6 on the enlarged head 4 of the spindle will 70 securely lock these parts together in operative position.

The outer circumference of the member 6 is formed with a beveled annular flange or the like 9, said beveled portion being preferably 80 provided with radially disposed projections or teeth 10, the purpose of which will be hereinafter more fully disclosed.

Also cooperating with the spindle 1 is a fork shaped member or driver 11 having a 85 base 12, a shank 13 preferably angular in cross section, and oppositely disposed parallel pins or prongs 14. This shank 12 is removably inserted in the chamber or recess 5 of the enlarged head 4 of the shank and maintained 90 in adjusted position, preferably by a spring pressed ball locking device 15, the shank being constructed with two small recesses 16 cooperating with the ball device in a well known manner. The shank is made slightly smaller 95 than the receiving chamber or recess 5, to provide a small amount of play or clearance, for the purpose to be hereinafter more fully explained.

In the practical use of the complete device, 100 and as supplied to the trade, the annular member 6 and the fork shaped driver 11 are in reality adapters to be furnished in different sizes, so that by a simple interchanging and manipulation of parts the improved assembly 105 is made capable of operation with pistons of various sizes.

Each adapter 6, as supplied, has the same diameter of tapered bore but a different size of flange 9, corresponding to the various sizes 110 of standard pistons. Likewise the adapters 11 all have the same size and shape shank 13 to

loosely fit the recess or chamber 5 of the spindle 1, but in each individual instance the size of the base 12 and the prongs 14 will vary, also according to the sizes of the various standard 5 pistons.

The beveled flange 9 of the annular member or adapter 6, may be plain but is preferably provided with the teeth 10 as shown, so that as the piston is adjusted in place and partially 10 rotated to engage the prongs of the driver 11, any chips or burrs left on the inner skirted beveled edge of the piston, will be removed and the piston will be truly and firmly seated in place.

15 Before the piston is placed into position on this device, the inner skirted edge is preferably beveled in a manner as shown in another application about to be filed by the present applicant.

20 As hereinbefore mentioned, the size of the shank 13 of the driver 11 is slightly less than the recess 5, so that there will be a small amount of play therebetween. This is desirable and necessary, so that in case there is 25 a slight difference in size and shape between the inwardly projecting piston pin receiving bosses, the driver 11 will be permitted to accommodate itself to these differences without straining the piston in an obvious manner.

30 It will be noted also, that the shank 13 is provided with two recesses 16 and the head 4 with only one ball locking device 15, so that the driver 11 may be moved outwardly and inwardly to accommodate the variable 35 location of the piston pin bosses.

In actual use only seven assorted sizes of 40 adapters are required to cover a range of sizes in diameter of pistons from $2\frac{1}{2}$ " to $5\frac{1}{2}$ ". Each specific diameter does not necessitate an adapter for that particular size, it being one of the objects of this invention to provide the smallest number of adapters to 45 cover the range and yet allow the cutting tool in case of a lathe, and the grinding wheel in case of a grinder to pass over the piston and beyond without coming in contact with the surfaces 10 thereby destroying this accurate surface for, in grinding (which is the final finishing operation) it is most desirable to have the grinding wheel pass completely over and beyond each end of the piston so that the entire surface of the grinding wheel may come in contact with the piston.

50 What I claim is:

1. The combination with a metal working machine, of a driving member provided with an enlarged chambered head, a removable annular member carried by said head and provided with a radially serrated beveled circumferential outer portion constructed and arranged to internally engage a hollow work 60 piece to center the same thereon, a fork shaped member removably secured in the chamber in said head, the forked end of said 65

latter member adapted to internally engage said work piece for rotating the same upon the rotation of the driving member.

2. The combination with a metal working machine, of a driving spindle provided with 70 an enlarged tapered head, a noncircular recess formed in said enlarged head, an annular member provided with a tapered bore and an outer circumferential beveled portion adapted to be removably secured on said tapered head, said beveled portion constructed and arranged to internally engage the skirted end of a piston to center the same thereon, a fork shaped member provided with a shank removably secured in the recess in said head, the forked end of said last 75 mentioned member constructed and arranged to internally engage said piston for rotating the same upon the rotation of the spindle.

3. The combination with a metal working 80 machine, of a driving spindle provided with an enlarged tapered head, a noncircular recess formed in said enlarged head, an annular member provided with a tapered bore and an outer circumferential radially grooved 85 beveled portion adapted to be removably secured on said tapered head, said beveled portion constructed and arranged to internally engage the skirted end of a piston to center the same thereon, a fork shaped member provided with a shank removably secured in the recess in said head, the forked end of said last 90 mentioned member constructed and arranged to internally engage said piston for rotating the same upon the rotation of the spindle.

4. The combination with a metal working machine for grinding pistons including a head stock and an axially aligned centering member, of a driving member provided with a chambered head mounted in the head stock, a removable annular member formed with an outer circumferential beveled portion carried by said chambered head, said beveled portion constructed and arranged to internally engage the skirt end of a piston to center the same thereon, cooperating with the aforementioned axially aligned centering member, and a fork shaped member removably secured in the chamber in said head, the forked end of said forked member constructed and arranged to internally engage said piston for rotating the same upon the rotation of the driving member.

5. The combination with a metal working 115 machine for grinding pistons, including a head stock and a centering tail stock, of a driving spindle provided with an enlarged tapered head mounted in the head stock, a noncircular recess formed in said enlarged 120 head, an annular member provided with a tapered bore and an outer circumferential radially grooved beveled portion adapted to be mounted on said tapered head, a cooperating cam slot and pin for removably securing 125 130

said annular member on the tapered head, said aforementioned beveled portion constructed and arranged to internally engage the skirted end of a piston to center the same thereon, cooperating with the center of the said tail stock, and a fork shaped member provided with a shank removably secured by a spring pressed retaining element, in the recess in said head, the forked end of said forked member constructed and arranged to engage the inwardly projecting piston pin bosses of said piston for rotating the same upon the rotation of the spindle.

In testimony whereof I affix my signature.

LOUIS A. DALL.
